UNITED STATES PATENT OFFICE.

IVAR CARL LARSON, OF EAST PROVIDENCE, RHODE ISLAND, ASSIGNOR TO BEACON PRESSED STEEL CO., OF PROVIDENCE, RHODE ISLAND, A CORPORATION OF RHODE ISLAND.

CURTAIN-ROD BRACKET.

Application filed August 25, 1925. Serial No. 52,311.

This invention relates to improvements in curtain-rod brackets of a type more particularly adapted to support curtains and over-drapery; and the object of this invention is to provide a bracket of this character having a plurality of curtain rod supporting means attached to a single plate.

A further object of the invention is to so flatten the portions of the curtain rod supporting arms which are in engagement with the plate that a relative turning movement between the plate and the arms is prevented.

A still further object of the invention is the flattening of the ends of the arms and notching them to form hooks for suitable engagement with the curtain supporting means.

The invention further consists in mounting a hook on one of the arms for engagement with an additional curtain supporting rod or the like.

With these and other objects in view, the invention consists of certain novel features of construction, as will be more fully described, and particularly pointed out in the appended claims.

In the accompanying drawings:

Figure 1 is a front elevation of a window with a shade, curtain and over-drapery 30 hung thereover.

Figure 2 is a perspective view of the plate and roller shade supporting arm formed integral therewith.

Figure 3 is a perspective view of the U-shaped arm adapted to be attached to the plate showing the same suitably flattened.

Figure 4 is a perspective view showing a pair of plates with outwardly-extending arms mounted thereon, hooks being mounted 40 on one of these arms and the curtain-supporting means mounted between the hooks and the ends of the arms.

Figure 5 is a modified form of plate showing the omission of the roller shade supporting means.

It is found in practice desirable to support a roller shade, curtains and over-drapery over a window and to provide a single pair of brackets for supporting these several distinct hangings, without the use of solder, which I have accomplished by providing a plate having an arm bent up at one side thereof for supporting the shade and having a pair of outwardly-extending wire arms attached to the plate by folding portions of

the plate over the wire, the wire being flattened at the plate-engaging portions to prevent a relative rotating movement between it and the plate, and further, I have provided hooks on the inner arm and have turned inwardly, flattened and notched the end portions of the arms to support a plurality of springs between the corresponding hooks of the pairs of brackets on which the curtain and over-drapery may be mounted; and the following is a detailed description of one means by which these advantageous results may be accomplished:—

With reference to the drawings, 10 designates a plate of suitable configuration having 70 fingers 11 cut from the stock of the plate and bent outwardly to be folded over the bridge portion 12 of the pair of arms 14 and 15 of the curtain rod supporting wire, the same being flattened as at 22 to prevent relative movement between the plate and the arms 75 after they have been securely rolled over this portion of the wire, as shown in Figure 4.

The ends of the arms 14 and 15 are curved inwardly on a long sweeping arc while being maintained in their substantially parallel relation and are flattened at their ends 16 and 17 and notched as at 18 and 19 to form hooks for engagement with suitable curtain supporting means which I have illustrated as 80 springs 20, provided with suitable eyes 21 for engagement with these hooks.

Also there may be mounted supplemental hooks 32 on the arms 15 of each pair of brackets between which an additional spring 90 may be supported, this hook being slidable along the arm to be moved back against the plate 10 when not in use.

The flattened portions 16 and 17 of the arms are substantially the diameter of the springs 20 so that the curtains or over draperies may be easily slid around the curved portions of the arms.

The plates are provided with suitable openings 23 for the reception of screws 24 100 for attaching the same to a window frame.

These brackets are adapted to be used in pairs and one of the pair of brackets may have an arm portion 25 bent inwardly at substantially right angles thereto and provided with an opening 26 to receive one end of the roller shade, while the other plate of the pair is provided with an outwardly bent arm 27 disposed at substantially right angles to its plate and is provided with an angularly- 105 110

shaped notch 28 to receive the opposite end of the roller shade in the customary manner. It will be seen that I have provided brackets having roller shade supporting means for supporting the shade 29 and also curtain-rod supporting arms for hanging a curtain 30 and two different over draperies 31 and 33, all as illustrated in Figure 1. However, it will be obvious that the arms at the edge of the plates may be omitted to provide a structure, as illustrated in Figure 5, where it is desired to mount a shade independently of the curtain rod brackets.

From the foregoing, it will be seen that I have provided curtain and roller shade supporting means which are simple in construction and yet effective in their operation and comparatively inexpensive to manufacture.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A curtain rod bracket comprising a plate, a U-shaped wire secured thereto to extend outwardly therefrom, the arms of said U being of unequal lengths and each bent in the same direction at substantially right angles and disposed in substantially the same

plane in spaced relation, said arms being adapted to engage a curtain-supporting means.

2. A curtain rod bracket comprising a plate, a wire folded to form spaced parallel arms with a flattened connecting bridge portion, and fingers raised from the stock of said plate and folded over said bridge portion to secure said wire in position, the ends of said arms being bent at substantially right angles and maintained in their spaced parallel relation.

3. A curtain support comprising a pair of spaced plates, each having a circular wire folded to form a pair of spaced parallel arms extending outwardly therefrom, the end portions of said pairs of arms being bent toward each other and flattened and notched to form hooks, and curtain supporting means detachably engaging said hooks and extending between corresponding arms.

4. A curtain support comprising a pair of spaced plates, each having a circular wire folded to form a pair of spaced parallel arms extending outwardly therefrom, said pairs of arms being bent toward each other at their ends and flattened and notched to form hooks, and a coiled spring detachably engaging said hooks and extending between corresponding arms for supporting curtains.

In testimony whereof I affix my signature.

IVAR CARL LARSON.
